CLAMP FOR DRAWBENCHES OR THE LIKE

William A. Weightman, Philadelphia, Pa., assignor to Edward G. Budd Manufacturing Company, Philadelphia, Pa., a corporation of Pennsylvania

Original application February 15, 1940, Serial No. 318,983. Divided and this application January 6, 1942, Serial No. 425,747

6 Claims. (Cl. 153—35)

This invention relates to a draw bench and more particularly to the clamping means whereby the work strip is held while it is drawn through forming rolls.

This application is a division of my application Serial No. 318,983, filed February 15, 1940, for Draw rolling machine, on which Patent No. 2,288,119 issued June 30, 1942.

It is an object of the invention to provide a clamping means for such machines which is rugged in construction, which is designed to permit the clamping reaction to be taken by a closed frame and to have the clamping force augmented by the member through which the draw pull is applied. The clamping means is further designed so that the greater the force of the draw, the greater the resulting reaction and clamping force, so that the work strip being drawn cannot become uncoupled from the drawing means during the drawing operation.

It is a further object to provide a clamping means which is readily adaptable or adjustable to different classes of work, and in which the clamping jaws proper are readily applied or removed to permit their replacement and adaptation to such different classes of work. The clamping means is further provided with a wide-based support suitably guided by anti-friction means in trackways offset from the line of draw of the work strip, thus preventing tilting of the carriage under the draw pull and its firm support under the forces involved in the draw.

Other objects and advantages and the manner in which they are attained will become clearer from the following detailed description when read in connection with the drawing appended hereto.

In the drawing:

Fig. 1 is a side elevational view of the drawing machine in its entirety with the invention shown applied thereto.

Fig. 2 is a transverse sectional elevation, on an enlarged scale, through the machine, showing parts of the draw clamp in section and part in elevation, the section being taken on approximately the line 2—2 of Fig. 1.

Fig. 3 is a fragmentary central longitudinal sectional view through the draw clamp and parts associated therewith, the section being on a scale similar to that of Fig. 2.

The machine to which the invention is shown applied may consist of a series of sets of mating rolls 10 which are arranged in such alignment that they can act upon the work strip 11, the section of which is to be formed, substantially in a common plane. Six sets of these rolls are

shown, but these may be, of course, more or less. They are commonly mounted on a supporting base 12. The strip material 11 may be supplied to the machine in the form of a coil which for convenience sake, may be mounted upon a rotating table or reel 13 having a vertical axis 14. The sheet strip 11 is threaded through all of the mating rolls and at its delivery end it is engaged by a draw clamp 16 mounted for longitudinal movement on the draw bench support through which clamp the draw pull is applied. This pull is applied by a chain 17 of a length adequate to traverse the clamp 16, a distance equal to the length of the elements to be formed from the work strip. Connection with the chain is by means of a hooked link 18. The chain is driven through a suitable reduction gearing 19 from the electric motor 19.

The draw clamp 16 comprises a rugged closed frame 20 carrying a pair of transversely extending vertically relatively adjustable clamps 21 fixed in longitudinal position in the frame 20 by the vertically extending gibs 22. The faces or jaws 23 of these clamps are shaped to accord with the section of the work strip 11 to be clamped, and to adapt the clamps readily to different work sections, the faces or jaws 23 are replaceable and removable by division generally in the horizontal plane of the bodies of the clamps 21 and connection therewith through transversely extending keys 24 and connecting bolts 25.

The upper of the clamps 21 may be raised and lowered by vertically adjustable screws 26 passing loosely through openings 27 in the top of the frame and having screw threaded engagement with longitudinal extending cylindrical bearing members 28 rotatable in bearings in the top of the frame 20. This support of the screws 26 permits slight tilting thereof without placing undue strain thereon.

The lower of the clamp bodies 21, however, is vertically adjustable through a longitudinally elongated and transversely widened wedge member 29. This long and wide wedge member 29 rests in a seat 30 formed in the long and wide bottom portion 21' of the closed frame 20 of the clamp. The closed frame 20 is preferably made in two parts bolted together by bolts 20a. The wedge member 29 is guided for longitudinal sliding movement in the seat 30 and extends into a corresponding seat 31 in the lower clamp body 21.

Vertical adjustment of the lower clamp body 21 is brought about by the longitudinal movement of the wedge member 29 under the draw pull on the strip 11. To this end the wedge 29 is con-

nected at its forward end by a hinge connection 32 to the draw link 18 having a hook or tooth 33 adapted to enter between two successive pins 34 of the draw chain 17, whereby the operation of the chain by the motor 19 in the direction indicated by the arrow, Fig. 3, drags the clamp 16 and hence draws the strip 11 through the rolls of the machine.

The wedge 29 is retained in a determinate normal position by one or more longitudinally extending studs 35 passed through the adjacent transverse wall 36 of the frame portion 20 and each having a biasing spring 37 surrounding it. Lock nuts 38 serve to adjust the tension of the spring 37 and in this way adjust the normal rearward position of the wedge with zero pressure on the spring.

The clamp 16 is provided with supporting legs 39 extending forwardly and rearwardly on each side of the chain 17. These legs bear at their extremities rollers 40 which travel in inwardly facing channel-section tracks 41 at opposite sides of the continuous longitudinally extending flooring 42 upon which the chain 17 travels. These legs afford an elongated travelling base for the clamp steadyng the clamp under the reactions of the work and chain thereon.

In operation, the strip 11 having been threaded through the rolls and the clamp 16 having been connected to the delivery end of the strip, the starting of the electric motor 19, with the link 18 hooked into the chain 17, applies pull to the clamp 16 and through it draws the strip 11 through the properly adjusted sets of mating rolls 10 to form the strip to its desired cross-section.

The pull of the chain by an offset vertically lower than the pull of the strip, imposes a torque upon the clamp 16 counter clockwise, as seen in Fig. 3. This torque is taken and effectively reacted in the frame of the machine by the elongated base afforded by the legs 39 from the clamp frame 20.

By reason of the wedging engagement of the wedge member 29 with the under longitudinally inclined face 31 of the lower clamp body 21, the stronger the pull, the tighter will the parts of the clamp be drawn together and in firm gripping engagement with the strip 11. The initial angle of the wedge 29 and the complementary face of the lower clamp body 21 is such that the upper clamp body 21 may be set up tightly against the lower without displacing the wedge 29. The reaction to the clamping force of the screws 26 is taken by the wedge 29 and the bottom 20' of the clamp frame 20. However, the pull of the chain 17 is applied directly to the wedge 29 through the hooked or toothed link 18, and the stronger the pull on the wedge, the tighter it is drawn, and the stronger becomes the clamping force of the jaws 23 of the clamp upon the end of the strip 11, the initial reactive force of the wedge being increased and converted into a more powerful clamping force, the screws 26 taking the reaction. Thus the strip cannot get away once the clamping jaws grip it.

In the foregoing description, a specific form of clamping device has been described, but it will be understood that applicant does not wish to be limited to the precise detail of the described embodiment, since the invention may obviously take other forms which would readily occur to those skilled in the art, and all such obvious modifications are intended to be covered in the appended claims.

I claim:

1. A clamp device for draw benches or the like comprising a clamp structure having legs extending in the direction of draw and forming a widened base for supporting and guiding it on a runway, clamping members in said structure adapted to receive and clamp between them the work being drawn, one of said clamping members being movable in said structure transversely to the direction of draw and toward and away from the other clamping member and having its clamping reaction taken up by a wedging means pointing in the direction of draw, and a draw connection from said wedging means to a source of power, the plane of said connection and the plane in which the work is clamped being offset from each other, the widened base opposing tilting of the clamp due to said offset relation.
2. In a clamping device for a draw bench or the like, a supporting structure, a pair of relatively movable clamping members arranged on said supporting structure and adapted to receive and clamp between them work to be drawn, guiding means on said structure adapted for guiding the latter on a predetermined path on the draw bench, and adjustable means between said structure and one of said clamping members adapted to regulate the alignment of such member with respect to said guiding means and thereby to the plane of draw, and means automatically actuated by the draw connection to a source of power to force the other clamping member toward said adjustable clamping member and to pull said structure with both clamping members and the work held between them.
3. In a clamp device for draw benches or the like, a supporting structure, a pair of clamping members, supported by said structure, adapted to receive and clamp between them work to be drawn, said clamping members being movable relatively to each other and to said structure, independently adjustable means between said structure and one of said clamping members to regulate the latter's alignment with respect to the plane of draw, and means automatically actuated by a draw connection to a source of power to force the other clamping member toward said first clamping member.
4. A clamp device for draw benches or the like comprising a clamp supporting structure, a pair of clamping members movable in said structure and relatively to each other, said clamping members being adapted to receive and clamp between them the work being drawn, means between said structure and one of said clamping members to regulate the alignment of this member with respect to the plane of draw, means between the other of said clamping members, said structure and a draw connection of the type forcing said other member the more tightly against the work and the first clamping member the stronger the draw is.
5. A clamp device for draw benches or the like comprising a structure having a wide base extending in the direction of draw and adapted for supporting and guiding it on a runway of the bench or the like, clamping members in said structure adapted to receive and clamp between them the work being drawn, one of said clamping members being movable in said structure and having its clamp reaction taken up by wedging means pointing in the direction of draw, and a draw connection from said wedging means to a source of power for tightening said wedging means and for pulling said device along the runway.

way of the bench, the plane of said connection and the plane in which the work is clamped being offset from each other, the wide base opposing tilting of the clamp due to said offset relation.

6. A clamp device according to claim 5 in combination with a draw bench or the like, a runway on said draw bench, one of said wide base of said

structure and said runway being formed with a channel extending in the direction of draw while the other one of said base and said runway has portions projecting into such channel so as to further assist in the opposing of the tilting of the clamp due to said offset relation.
